PROCESS FOR PRODUCTION OF CYCLOHEXANE

Ernest F. Pevere, Beacon, and George B. Arnold, Fishkill, N. Y., assignors to The Texas Company, New York, N. Y., a corporation of Delaware

Application December 9, 1954, Serial No. 474,158

2 Claims. (Cl. 260—666)

This invention relates to an improved process for producing cyclohexane, and more particularly to such process for producing synthetic cyclohexane.

The demand for this hydrocarbon has been constantly increasing, especially for use as an intermediate in the production of synthetic fibers such as polyamides.

The so-called naphthenic distillates such as straight run distillates from naphthenic petroleums, preferably those having boiling point range at atmospheric pressure of 150° to about 180—225° F. are the principal starting materials for practice of our process. Other distillates containing saturated straight and branched chain and cyclic hydrocarbons and including in their composition methylcyclopentane, cyclohexane, and other mixed aliphatic hexanes and heptanes are suitable feed stocks. While it might appear that recovery of the cyclohexane from such mixtures is simply a distillation problem, actually it is exceedingly complex because cyclohexane boils either very close to or within the boiling range of the paraffinic hydrocarbons present.

Our improved process comprises: stripping the major quantity of methylcyclopentane from a mixed hydrocarbon feed containing saturated straight chain and branched chain hydrocarbons including methylcyclopentane, cyclohexane, aliphatic hexanes, and heptanes, thereby leaving a liquid residue containing cyclohexane in association with hydrocarbons having boiling point above that of methylcyclopentane; fractionally distilling from said residue a cyclohexane enriched distillate; isomerizing the major fraction of the cyclohexane in said cyclohexane enriched distillate into additional methylcyclopentane by contacting said cyclohexane enriched distillate in vapor phase with an isomerization catalyst at temperature of 800—900° F. and pressure of 500—2000 p. s. i. g.; recovering catalytically-formed additional methylcyclopentane from at least part of the isomerized mixture; conducting the recovered catalytically-formed additional methylcyclopentane and said major quantity of methylcyclopentane previously stripped and hydrogen into contact with a hydroforming catalyst at temperature maintained from 840—980° F. and pressure from 250 to 500 p. s. i. g., thereby reforming a substantial proportion of the methylcyclopentane so contacted into benzene and hydrogen; converting said benzene into a cyclohexane-containing hydrogenation product by catalytic hydrogenation with hydrogen at temperature from 600° to 750° F. and pressure of 500 to 1000 p. s. i. g., and fractionally distilling cyclohexane from the cyclohexane-containing hydrogenation product.

Advantages of our process include high yield of cyclohexane from the hydrocarbon feed and avoidance of expensive recovery procedures such as solvent extraction, extractive distillation or azeotropic distillation for clean separation of the desired hydrocarbon fractions, thereby permitting efficient and simple fractional distillation at modest pressure to be used in all stages of the process.

The cut points for methylcyclopentane distillations in our process should be sharp and so adjusted that the

2

overhead distillate contains virtually no cyclohexane. Distillate having an atmospheric boiling point range of for example, 160—165° F., is a typical methylcyclopentane fraction of desired quality. Residue from this operation, 5 a mixture consisting essentially of cyclohexane together with associated hydrocarbons having atmospheric boiling point above that of methylcyclopentane, is further fractionated (stripped) to obtain a cyclohexane enriched distillate (also containing associated hydrocarbons such as isomeric heptanes, this distillate having atmospheric boiling point of, for example, between about 165° and about 180—200° F.). Such distillate is then contacted in vapor phase with an isomerization catalyst such as a noble metal or nickel or cobalt on HF-treated alumina at temperature of 700—900° F. and pressure of 500—2000 p. s. i. g. to convert the major portion of the cyclohexane in the cyclohexane enriched distillate into additional methylcyclopentane.

Figure 1, hereinafter discussed shows one embodiment 20 of our process wherein the isomerized mixture, containing the catalytically-formed additional methylcyclopentane is split into two portions; one portion is returned into admixture with the hydrocarbon feed mixture entering the primary methylcyclopentane stripping operation in 25 order to recover recycled methylcyclopentane and unconverted cyclohexane; catalytically-formed additional methylcyclopentane is separated from associated higher boiling materials by fractional distillation of the other portion of the mixture.

Figure 2, hereinafter discussed, shows another embodiment 30 of our process wherein the entire isomerized mixture containing the catalytically formed additional methylcyclopentane is sent directly to a fractional distillation. Catalytically-formed additional methylcyclopentane is separated from associated higher boiling materials including unconverted cyclohexane by fractional distillation. The bulk of these higher boiling materials are recycled into the isomerization reactor along with the cyclohexane-enriched distillate to recover additional 35 cyclohexane values. The balance of the high boilers are purged from the system. A useful variation on this procedure is to recycle most of the higher boiling materials including unconverted cyclohexane into fractional distillation along with the cyclohexane-containing residue 40 from the primary methylcyclopentane stripping operation to form an additional quantity of the cyclohexane enriched distillate for feeding to the isomerization reactor. The balance of the high boilers are purged from the 45 system as before.

The distillates which consist essentially of methylcyclopentane are combined and catalytically treated in the 50 presence of hydrogen under conditions which are substantially equivalent to the conditions commonly employed in hydroforming higher boiling gasolines. Such 55 conditions will be referred to hereinafter as "hydroforming conditions," and the catalyst used will be referred to as "hydroforming catalyst." The following approximate limits can be used in the hydroforming:

	General	Preferred
Temperature, ° F.....	850—950	875—900
Pressure, p. s. i. g.....	250—500	500
Liquid hourly space velocity, volumes per hour.....	2—5	3
Volume of catalyst per hour.....	200—450	400—450
Partial pressure of hydrogen.....		

Regeneration of the hydroforming catalyst is done preferably at frequent intervals, i. e., 1—2 hours, in order to 70 maintain a high conversion of methylcyclohexane into benzene. By hydroforming the methylcyclopentane is converted largely into benzene and hydrogen.

The hydroformed product is then hydrogenated catalytically with hydrogen to convert benzene into cyclohexane. Hydrogenation can be operated at temperature from 600° to 800° F. and pressure of 500 to 1000 p. s. i. g., preferably about 700° F. and 700 p. s. i. g. Suitable hydrogenation catalysts are nickel-tungsten sulfide, cobalt molybdate, and molybdena on alumina. The resulting cyclohexane-containing hydrogenation product is freed of hydrogen gas and fractionally distilled to prepare high purity cyclohexane as a bottoms fractions. At least part of the low boilers obtained in the final fractionation can be blended with the hydrocarbon feed mixture for recovery of cyclohexane and methylcyclopentane values.

Advantageously, the quantity of the additional methylcyclopentane-containing mixture (resulting from isomerizing the cyclohexane-enriched fraction) which is recycled to form a blend with the hydrocarbons fed to the primary methylcyclopentane stripping operation is controlled to establish and maintain mol ratio of cyclohexane:total associated hydrocarbons in the resulting blend, exclusive of methylcyclopentane, not substantially below about 0.05:1 and preferably above about 0.1:1. By so regulating this recycle the efficiency and economy of the subsequent steps, i. e., the fractional distillation and the catalytic isomerization of the cyclohexane-enriched fraction, is substantially increased.

The drawings are flow diagrams showing ways of operating our process. Pumps, compressors, and controllers of flow, temperature, and pressure (not shown), are supplied where necessary or desirable. The specific example below is described with particular reference to the Figure 1. All percentages are mol percentages and all parts are mol parts unless otherwise specified.

Example

3700 parts of straight run naphthenic distillate from California petroleum having boiling range of about 158 to 225° F. at atmospheric pressure and containing 5% light ends, 10% cyclohexane, 10% methylcyclopentane, and balance of associated hydrocarbons is fed through lines 9 and 10 into fractionating tower 11 wherein hydrocarbons having atmospheric boiling point below 160° F. are separated and withdrawn through line 12. Thus stripped, the remainder of the naphthenic distillate, 3515 parts, is withdrawn through line 13. The stripped remainder is passed through line 14 into fractionating tower 15 together with 750 parts recycle hydrocarbons from line 25, obtained as hereinafter described. A methylcyclopentane cut, 640 parts, having boiling point range at atmospheric pressure at 160-170° F., is withdrawn through line 16. The residue consisting of cyclohexane and other higher boiling hydrocarbons is withdrawn through line 17 and passed into fractionating tower 18 wherein 3625 parts of a mixture of cyclohexane and associated hydrocarbons (principally mixed heptanes) having atmospheric boiling point between 170° and 200° F. is separated and withdrawn through line 20, heated in exchanger 21, and passed through line 22 into catalyst case 23. High boiling residue, 2625 parts, is withdrawn from tower 18 through line 19.

Catalyst case 23 is packed with cobalt on HF-treated alumina. Flow thereover is maintained at liquid space velocity of 0.5 volume per volume of catalyst. Temperature of this operation is maintained at 850° F. and average pressure of 1500 p. s. i. g. whereby the major portion of the cyclohexane in the mixture is converted into additional methylcyclopentane. The catalytically treated mixture, 1000 parts, is withdrawn through line 24. A quarter of it is sent to fractionating tower 27 through line 26. The remainder is recycled through line 25 for subsequent separation in tower 15. The resultant composition fed to tower 15, formed by the mixing of the stripped naphthenic distillate and said recycled remainder, has ratio of cyclohexane:associated hydrocarbons exclusive of methylcyclopentane of about 0.124:1.

In tower 27 additional catalytically-formed methylcyclopentane, 90 parts, is stripped from said quarter of the catalytically treated mixture, and the higher boiling materials are purged from line 29. The 90 parts of the 5 additional catalytically-formed methylcyclopentane are withdrawn through line 28, combined with that flowing in line 16, and this blend passed through line 31 into catalyst case 33 with recycled hydrogen flowing in from line 32 from a source described hereinafter.

- 10 Catalyst case 33 is packed with platinized HF-treated alumina pellets and conditions therein are: temperature of 875° F.; pressure of 500 p. s. i. g.; and liquid space velocity of 3.0 volumes per volume of catalyst per hour, whereby preponderantly benzene and hydrogen are 15 formed from the methylcyclopentane fed. The mixture is conducted from catalyst case 33 through line 34 and mixed with additional hydrogen, 600 parts, entering inlet 35. The combined flows are then passed into hydrogenator 36, packed with tungsten sulfide-coated alumina 20 pellets. Conditions of hydrogenation are 600° F., 1000 p. s. i. g., and liquid space velocity (exclusive of hydrogen) of 0.5 volume per volume of catalyst per hour whereby the catalytically-formed benzene is substantially entirely converted into cyclohexane.
- 25 The hydrogenation product is withdrawn through line 37, condensed in exchanger 38, and passed through line 39 into vessel 40. Gaseous hydrogen is separated and recycled through line 32 as previously described with a hydrogen purge being taken off line 47. Separated liquid 30 is passed through line 41 into fractionating tower 42 wherein 140 parts of hydrocarbons having boiling point below cyclohexane are fractionally distilled and withdrawn from line 43. A purge fraction of this distillate can be withdrawn from line 45, and the remainder can 35 be recycled to blend with the straight run naphtha feed entering line 9. From line 46 there is withdrawn purified hydrogenation product containing 590 parts cyclohexane.

- The operations depicted in Figure 2 are similar to 40 those of Example 1 and use essentially the same equipment items as are shown in Figure 1 except that: the entire isomerized mixture from catalyst case 23 is passed into tower 27 for fractionation instead of being recycled in part to tower 15; catalytically-formed additional 45 methylcyclopentane is stripped in tower 27 and withdrawn through line 28 while the bulk of the resulting residue is recycled through line 48 into exchanger 21 for isomerization processing; and sufficient purge of the resulting residue is withdrawn from tower 27 by line 29 to 50 prevent reduction of the mol ratio of cyclohexane:other hydrocarbons in the isomerization reactor feed to a value below about 0.1:1.

- Obviously many modifications and variations of the 55 invention, as hereinbefore set forth, may be made without departing from the spirit and scope thereof and, therefore, only such limitations should be imposed as are indicated in the appended claims.

We claim:

1. A process for production of cyclohexane comprising: forming a feed mixture of a petroleum distillate having boiling point range between about 160° and about 60 225° F., said petroleum distillate containing methylcyclopentane, cyclohexane, and associated hydrocarbons with the ratio of cyclohexane to said associated hydrocarbons 65 above about 0.1:1, and a portion of recycled isomerization reaction product containing additional catalytically-formed methylcyclopentane and unreacted cyclohexane, said portion being obtained from a later stage of the process and its quantity being regulated for maintaining 70 the ratio of cyclohexane to associated hydrocarbons in said feed mixture at a value above about 0.1:1; stripping a methylcyclopentane-rich fraction having boiling point range between about 160° and about 170° F. from said feed mixture, thereby leaving a liquid residue containing 75 cyclohexane together with associated hydrocarbons;

stripping a cyclohexane-enriched distillate from said residue; isomerizing the major fraction of cyclohexane in said cyclohexane-enriched distillate into additional methylcyclopentane by contacting said cyclohexane-enriched distillate in vapor phase with an isomerization catalyst at a temperature of 800-900° F. and a pressure of 500-2000 p. s. i. g.; recycling a fraction of the isomerization reaction product into admixture with said petroleum distillate for forming said feed mixture; recovering additional catalytically-formed methylcyclopentane from the balance of the isomerization reaction product; conducting the recovered additional catalytically-formed methylcyclopentane, the methylcyclopentane previously stripped from the feed mixture, and hydrogen into contact with a hydroforming catalyst at a temperature maintained between 840° and 980° F. and a pressure between 250 and 500 p. s. i. g., thereby reforming methylcyclopentane into benzene and hydrogen; converting said benzene into a cyclohexane-containing hydrogenation product by catalytic hydrogenation with hydrogen at a temperature from 600° to 800° F. and a pressure of 500 to 1000 p. s. i. g.; and fractionally distilling cyclohexane from the resulting hydrogenation product.

2. A process for production of cyclohexane comprising: forming a feed mixture of a petroleum distillate having boiling point range between about 160° and about 225° F., said petroleum distillate containing methylcyclopentane, cyclohexane, and associated hydrocarbons with the ratio of cyclohexane to said associated hydrocarbons above about 0.1:1, and a portion of recycled isomerization reaction product containing additional catalytically-

formed methylcyclopentane and unreacted cyclohexane, said portion being obtained from a later stage of the process and its quantity being regulated for maintaining the ratio of cyclohexane to associated hydrocarbons in 5 said feed mixture at a value above about 0.1:1; stripping a methylcyclopentane-rich fraction having boiling point range between about 160° and about 170° F. from said feed mixture, thereby leaving a liquid residue containing cyclohexane together with associated hydrocarbons; 10 stripping a cyclohexane-enriched distillate from said residue; isomerizing the major fraction of cyclohexane in said cyclohexane-enriched distillate into additional methylcyclopentane by contacting said cyclohexane-enriched distillate in vapor phase with an isomerization catalyst at a temperature of 800-900° F. and a pressure of 15 500-2000 p. s. i. g.; recycling a fraction of the isomerization reaction product into admixture with said petroleum distillate for forming said feed mixture; recovering additional catalytically-formed methylcyclopentane from the balance of the isomerization reaction product; and converting the recovered additional catalytically-formed methylcyclopentane and the methylcyclopentane previously stripped from the feed mixture into cyclohexane.
